United States Patent Office

Des. 195,640
Patented July 9, 1963

195,640

DISHWASHER

Duane A. James, Richardson, Tex., assignor, by mesne assignments, to Ling-Temco-Vought, Inc., Dallas, Tex., a corporation of Delaware

Filed Dec. 4, 1961, Ser. No. 67,794

Term of patent 14 years

(Cl. D49—1)

Fig. 1.

Fig. 2.

Fig. 3.

Fig. 4.

Fig. 5.

FIG. 1 is a perspective view of a dishwasher embodying my design, the lines in the panel of the door indicating ribbed glass and the panel to the left of the door is shaded to show contrast.

FIG. 2 is a front elevational view thereof.

FIG. 3 is a plan view thereof.

FIG. 4 is an end elevational view thereof.

FIG. 5 is an elevational view of the end opposite that shown in FIG. 4.

The rear not shown is substantially plain.

I claim:

The ornamental design for a dishwasher, as shown and described.
